United States Patent Office.

E. A. CROWNHART, OF BRIDGEPORT, NEW YORK.

Letters Patent No. 90,641, dated June 1, 1869.

IMPROVED TRACE-BUCKLE.

The Schedule referred to in these Letters Patent and making part of the same.

To all whom it may concern:

Be it known that I, E. A. CROWNHART, of Bridgeport, in the county of Madison, and State of New York, have invented a new and improved Trace-Buckle; and I do hereby declare that the following is a full, clear, and exact description thereof, which will enable those skilled in the art to make and use the same, reference being had to the accompanying drawings, forming part of this specification, in which—

Figure 1 is a side view;

Figure 2 is a sectional side view; and

Figure 3 is a front view.

Similar letters of reference indicate like parts in all the figures.

This invention consists in a buckle-frame having a wide, flat web or bearing for the tug to rest against, and a corresponding flat plate, which is pivoted to the outer parts of the buckle-frame, and provided with a fixed tongue and also a thumb-piece or projection for opening the buckle; the arrangement of said plates being such as to hold the tug fair and straight, and give a degree of clamping-pressure when strain is brought upon the tug, as hereinafter more fully described.

In the accompanying drawings—

A is the tug;

B is the hames-tug;

C is the buckle-frame; and

D is the swinging tongue-plate.

The buckle-frame A is cast with a broad, flat web or backing, c c, as shown in fig. 2, and with a pair of ears, e e, to which is pivoted a flat plate, D, by means

of pivot f, said plate having a fixed tongue, d, fig. 2, and also a projection, g, which serves as a handle for opening the buckle.

When strain is applied to the tug A, the tongue-end of plate D is forced down, and the tug is compressed between the plates D and c, and is held by means of said pressure, and by the tongue d, engaging with holes in the tug, as usual.

The heel i, of the plate D, can be extended sufficiently to the rear to prevent the buckle from opening too easily, so the tongue will not become disengaged incidentally while the tug is slack.

I do not claim separately either a buckle-frame having a broad, flat bearing-surface, or a pivoted eccentric clamping plate, as I am aware that these features, so considered, are old; but having thus described my invention,

What I claim as new, and desire to secure by Letters Patent, is—

The trace-buckle, consisting of the frame C, curved up at the front, and cast with the broad, flat bottom c, ears e e, and side loops, and the clamping-plate D hung on rod f, between the ears e e, and having the projection d, heel i, and part g, all constructed and arranged substantially as herein described.

The above specification of my invention signed by me, this 2d day of March, 1869.

E. A. CROWNHART.
